DESIGN FOR A HOLDER FOR TOWELS AND SIMILAR ARTICLES

William O. Dailey, Portland, Oreg.

Application May 13, 1938, Serial No. 77,158

Term of patent 3½ years

To all whom it may concern:

Be it known that I, William O. Dailey, a citizen of the United States and a resident of the city of Portland, Multnomah County, and State of Oregon, have invented a new, original, and ornamental Design for a Holder for Towels and Similar Articles, of which the following is a specification, reference being made to the accompanying drawing, which forms a part thereof.

towels and similar articles, showing my new design;

I claim:

The ornamental design for a holder for towels and similar articles, as shown.

WILLIAM O. DAILEY.
